MEANS FOR COMPARING TIME MECHANISMS

Filed Dec. 30, 1927

UNITED STATES PATENT OFFICE

JOHN L. ALDEN, OF WYNCOTE, PENNSYLVANIA, AND CHARLES J. McCARTHY, OF EAST ORANGE, NEW JERSEY, ASSIGNEES, BY MESNE ASSIGNMENTS, TO WESTERN ELECTRIC COMPANY, INCORPORATED, OF NEW YORK, N. Y., A CORPORATION OF NEW YORK

MEANS FOR COMPARING TIME MECHANISMS

Application filed December 30, 1927. Serial No. 243,545.

This invention relates to means for comparing time mechanisms and more particularly to means for regulating watches.

An important problem that arises in connection with the regulation of watches or other timepieces is to determine when proper adjustment has been made. In general the principle involved in regulating watches is to compare the watch to be regulated with a standard timepiece. On account of the small periods of time involved and the tendency of individuals to differ in the accuracy of their observations, some means, utilizing a method other than a method of direct comparison, is exceedingly desirable.

An object of the present invention is to provide efficient means for comparing a time mechanism to be adjusted with a time standard.

Another feature of the invention is an indicating mechanism controlled by a timepiece to be adjusted and by a time standard whereby the relative rate of the timepiece is indicated.

Another feature is a rotatable indicator adapted to be controlled by the conjoint action of electrical impulses produced by a time standard and electrical impulses corresponding to movements of a timepiece to be compared.

A specific feature is a timepiece oscillatory support or vibrating reed having connection with a microphone whereby the mechanical vibrations generated by the pulsations of a timepiece may be amplified and translated into electrical impulses.

Another feature is an electrical system comprising a switch controlled by a standard timepiece and a second switch controlled by a timepiece to be adjusted, said switches being included in a control circuit for the operating mechanism of an indicating device.

Broadly the invention comprises a device having intermittent movement or mechanical vibration, means sensitive to vibrations of the device for converting these vibrations into electrical wave impulses, an indicator, the movement of which is controlled by an electric current and relay means sensitive to the waves and adapted to produce variations in

the current flow corresponding to these waves. The circuit of the electric current includes a plurality of devices, one controlled by said impulse and the other by a time standard. The electric current is rendered effective to actuate the indicator during an interval, determined by the time standard, a number of times corresponding to the number of electric impulses occurring during the interval.

The invention finds practical embodiment in a system for comparing the rate of a timepiece of unknown rate with a timepiece of known rate.

Additional features and objects will appear from the following description taken in connection with the accompanying drawing.

In the one figure of the drawing there is shown a system for comparing a timepiece to be adjusted with a time standard.

The system shown in the drawing includes a watch 10 held in a supporting fixture 11 in mechanical connection with a microphone 12. There is also included an indicator 20, a standard clock or time standard 13, a rotary switch actuating device 16, an indicator control circuit 20' and a starting switch 34.

The supporting fixture 11 for watch 10, which is mounted on a base 11' comprises an oscillatory reed 21 having a laterally projecting member 22 including a horizontal portion 23 and a vertical portion 24. The reed 21 supports clamp elements 25 and the member 22 supports a cooperating clamp element 26. The clamp element 26 includes a shank inserted through a hole in the vertical portion 24. The shank is slidably and is yieldingly pressed against the watch 10 by a flat spring 27. The microphone 12 is mounted on the upper end of the reed 21 in any suitable manner.

One electrode of the microphone is electrically connected to one terminal of the circuit of a relay 18, including a battery 17 and the other electrode is connected to the other terminal of this circuit. The microphone is of any well known construction for example of the type disclosed in Patent 1,426,757 to C. R. Moore of August 22, 1922, and represents any suit-

able means for converting mechanical movements into electrical impulses.

The standard clock 13 is adapted to actuate a switch 14 in any suitable manner. This switch is included in a circuit with the winding of magnet 15 and this circuit may be traced through the battery 33, to the movable arm of switch 34, movable arm of switch 16', winding of magnet 15 to switch 14. The device 16 includes a rotatable disc or ratchet wheel 35 connected by a shaft 36 to a second disc 37 on the edge of which the movable arm of switch 16' rides. The disc 37 includes a notch 38 into which the end of arm 16' is adapted to fall once during each revolution. When the arm 16' is in the notch the switch is open and the magnet 15 is released. This arrangement renders the indicator 20 inoperative until the first tick of the standard 20 clock, i. e., closure of contact 14, after the closure of switch 34. The ratchet wheel 35 is engaged by a pawl 39 pivoted to the armature 40 of magnet 15. This armature is connected to a spring 41 and is adapted to retract the pawl when the magnet 15 is released.

The indicating device 20 includes a similar disc or ratchet 42 with graduations 43 and a pointer 48. A pawl 44 adapted to engage the toothed periphery of the disc 42 is pivoted to the end of an armature 45 which in turn is pivoted at the point 46 and is adapted to be attracted by the magnet 31. A spring 47 is attached to the armature 45 whereby it may be retracted when the magnet 31 is released.

The indicator control circuit includes the winding of magnet 31 in series with switch 19, battery 32 and switch 16'. It will be evident that both switches 19 and 16' must be closed before a current can flow in this circuit.

The device herein described operates in the following manner: When an operator desires to regulate a watch he places it in the clamps 25, 26 and closes the manual switch 34, which is normally held open by a spring 34'. The vibrations or mechanical pulsations of the watch 10 are transmitted through the watch 50 casing to the reed 21 and thence with a certain amplification to the microphone 12. The resistance of the microphone is accordingly lowered and the current flowing in the circuit of the relay 18 connected to the 55 microphone is correspondingly increased. This increase or impulse of current causes the relay 18 to attract its armature thus closing the switch 19. At the cessation of the pulsation or tick the resistance of the microphone is restored, the current is reduced and the relay 18 releases its armature, whereupon the switch 19 is opened. The switch 19 thus opens and closes once for each pulsation of the watch.

65 The closure of switch 34 prepares the cir-

cuit of magnet 15 and upon the closure of switch 14 the magnet 15 attracts its armature. The switch 14 is preferably adapted to be closed once each second by the standard clock; however, it may be closed at other intervals if desired. Upon the subsequent opening of the switch 14, the magnet 15 releases its armature which is retracted by spring 41 actuating pawl 39 thus causing the ratchet to rotate a distance equal to the pitch 75 between adjacent teeth. If the magnet 15 operates once each second the ratchet preferably has 61 teeth so that the switch 16' will be closed during an interval of one minute.

During the interval that switch 16' is closed, the switch 19 successively closes and opens the control circuit of magnet 31 of indicator 20, thereby interrupting the current in this circuit. At each closure of switch 19, magnet 31 attracts its armature and with it the pawl 44 and at each opening of switch 19, magnet 15 releases its armature whereupon the pawl 44, actuated by spring 47, moves the disc 42 through an arc corresponding to the pitch of the teeth. Assuming that the watch 10 is properly regulated and ticks once each one-fifth second, then the disc 42 should have 300 teeth. Thus during a one minute interval the disc 20 will be rotated one complete revolution and the zero on the scale 95 will stop opposite the pointer 48. If, however, watch 10 is not correctly regulated the disc 42 will be rotated more or less than one revolution and the pointer 48 will indicate with respect to the scale on the disc the 100 number of one-fifth seconds the watch is fast or slow. The graduations on the disc are here assumed to be spaced a distance equal to the pitch of the teeth on the ratchet.

At the sixty-first actuation of the magnet 15 105 the arm of switch 16' falls into notch 38 and opens the indicator control circuit stopping the indicator.

Although a microphone has been described for translating the pulsations of the watch 110 into electrical impulses, any other suitable device, such as a piezo-electric or photo-electric device, may be substituted therefor.

If desired the standard clock and rotary switch may be associated with other indicators and their control circuits, whereby one operator may adjust several watches simultaneously. This may be done by connecting the control circuit of other magnets 31 to the leads 50 and 51 in the same manner as in the 115 control circuit of the magnet 31, shown in the drawing.

If it is desired to have a run longer than one minute the number of teeth on the ratchet wheel 35 may be correspondingly increased. For example, if a two minute run is desired the wheel 35 should have 121 teeth. In this case, the ratchet 42 may have the same number of teeth as before or it may be 125 provided with 600 teeth.

After the operator has taken the reading resulting from a run, the ratchet wheel 42 may be reset manually to its starting or normal position, that is, with the "0" position 5 on the dial directly opposite the arrow on the pointer 48. The operator then removes the watch under test and replaces it by another one, closes the switch 34 and the circuit automatically repeats the operation described above.

Although this invention has been described in connection with a specific embodiment, the principles involved are susceptible of numerous other applications that will readily occur to persons skilled in the art and it is to be limited, therefore, only as indicated by the scope of the appended claims.

What is claimed is:

1. In a time indicating system, a base, an oscillatory reed having one end secured to said base, means carried by said reed at a point adjacent said base for supporting the timepiece, a microphone mounted on the free end of said reed for receiving amplified impulses from the timepiece, and a work circuit connected to said microphone.

2. In a time indicating system, a base, an oscillatory reed having one end secured to said base, means carried by said reed adjacent 30 said base for supporting the timepiece, a microphone mounted on the free end of said reed for receiving amplified impulses from the timepiece, a circuit for said microphone including a source of current, and a magnet 35 energized through the operation of said microphone, said magnet having an armature, an indicator, a motor magnet for actuating said indicator, a circuit for said motor magnet including a source of current, a normally 40 open switch and said armature, means operable for closing said switch to cause the operation of said motor magnet for actuating said indicator according to the operation of said microphone, means for opening said 45 switch and a standard clock for controlling the operation of the last mentioned means.

3. In a time indicating system, a base, an oscillatory reed having one end secured to said base, a pair of jaw members carried by 50 said reed at a point adjacent said base for supporting the timepiece, a microphone mounted on the free end of said reed for receiving amplified impulses from the timepiece, a circuit for said microphone including 55 a source of current, and a magnet alternately energized through the operation of said microphone, an armature actuated by said magnet, an indicator, a motor magnet for actuating said indicator, a circuit for 60 said motor magnet including a source of current, and said armature and a contact arranged to be engaged by said armature for alternately closing and opening the last mentioned circuit, a normally open switching device in the last mentioned circuit, manually 65

operable means for closing said device for causing the operation of said indicator, a time standard, and a camming mechanism operable under control of said standard for actuating said switching device after a predetermined lapse of time for stopping the operation of said motor magnet.

4. In a vibratory mechanism for amplifying the vibration of a timepiece, said mechanism comprising an oscillatory reed having one end secured to a base and a clamping device for the timepiece carried by said reed adjacent its secured end whereby the vibrations of the timepiece are amplified at the free end of the oscillatory reed.

In witness whereof, we hereunto subscribe our names this 23rd day of December, 1927.
